UNITED STATES PATENT OFFICE.

LACHLAN W. McARTHUR, OF MONTREAL, WEST, QUEBEC, CANADA, ASSIGNOR TO HIMSELF, AND PERCIVAL STAFFORD MCKERGOW, OF WESTMOUNT, QUEBEC, CANADA.

KILN.

1,199,015.

Specification of Letters Patent. Patented Sept. 19, 1916.

Application filed February 16, 1916. Serial No. 78,652.

To all whom it may concern.

Be it known that I, LACHLAN WALLACE McARTHUR, residing in the town of Montreal, West, Province of Quebec, Dominion 5 of Canada, have made certain new and useful Improvements in Kilns; and I do hereby declare that the following is a full, clear, and exact description of my invention.

My invention relates particularly to up-draft kilns, and has for its object to obtain 10 from an open kiln the advantages of a closed kiln; and a further object is to obtain controlled direct heating from below. To this end I equip an open chamber kiln 15 with a series of floor grids each presenting tortuous flues and communicating with an individually controlled heat generator, the walls of the kiln-chamber being furnished with a series of draft flues located near the 20 top thereof and leading from the kiln-chamber to combustion chambers within the side walls and communicating with the kiln chamber and a series of chimneys. These combustion chambers have the effect of retaining 25 the burning gases in intimate relation with the kiln-chamber until practically complete combustion is obtained. For full comprehension, however, of my invention reference must be had to the accompanying 30 drawings forming a part of this specification, in which similar reference characters indicate the same parts and wherein:

Figure 1 is side elevation of a two chamber kiln partly in vertical sectional view, 35 the section being taken on line 1 1 Fig. 2, erected according to my invention; Fig. 2 is a part plan and part horizontal sectional view thereof, the section being taken on line 2 2 Fig. 3; Fig. 3 is a transverse vertical 40 sectional view taken on line 3 3 Fig. 1; Fig. 4 is a detail fragmentary elevation of one of the grids drawn to a larger scale; Fig. 5 is a detail sectional perspective view 45 of one of the furnaces and drawn to a larger scale and Fig. 6 is a detail perspective view of one of the upper slabs of the grids, drawn to a larger scale.

In erecting my improved kiln the ground upon which it is to stand is excavated in a 50 series of parallel furnace chambers *b* disposed in alined pairs, separated by the unexcavated portion *c* forming a wall, the oppo-

site ends of the excavation being open. These open ends are excavated to a greater depth to provide the furnace chamber 55 proper *e*, this furnace chamber being lined as usual with refractory material and the surface of the higher level floor *f* is also covered with refractory material while the inner ends of the excavations presented by 60 the division wall *c* are inclined upwardly toward each other as at *g*.

Side walls *k* and end walls *m* are erected in line with and above the open ends of these excavations thus forming an oblong 65 chamber inclosed on four sides. The roofs of the excavations are in the form of grids consisting of two layers, the first layer being slabs *p* resting at their ends on the opposite edges of the excavations and spaced 70 slightly from the side walls and from one another, the upper layer consisting of similar slabs *r* provided with corner feet *s* and these upper slabs being arranged over the spaces between the lower slabs, thus with 75 these lower slabs presenting a multiplicity of tortuous flues. The grids thus produced extend from the division wall *c* to the side walls. Each furnace chamber may be provided with a grate *t* suitable for burning 80 coal, and pipes *u* and *v* for liquid fuel or gas. When coal is to be burned the pipes *v* are removed.

The top of each side wall and the corners of the kiln are provided with a series of 85 chimneys *2* located preferably near the outside portions of the wall, and the extended thickness of the side walls beneath the chimneys are provided with narrow combustion-chambers *3* extending from end to end 90 of each of these side walls and from the top thereof to within a short distance of the fire box, the upper portions of these side walls being provided with a series of flues *4* effecting communication between the kiln- 95 chamber and the combustion-chambers; while the draft flues of the chimneys are extended downwardly as at 5 to within a short distance of the bottom of the combustion-chambers and have their lower ends 100 turned horizontally as at 6 into communication with the lower portion of the combustion-chambers. The effect of these combustion-chambers is that radiation of heat

through the walls containing them is prevented, and the burning gases which would otherwise escape from the chimneys are held within the walls a sufficient time to practically complete the combustion of the inflammable gases before they reach the atmosphere. These combustion-chambers may be terminated above the heat radius of the furnaces.

I find that the efficiency of my improved kiln is increased by extending the length and dividing it by a division wall 10 into a pair of kilns, as shown in Figs. 1 and 2. This kiln is intended primarily for the burning of brick and in order to dry out the moisture, or a portion of it, from the green brick they are usually placed in a drier and my invention is well adapted to use the waste heat from the burning operation to effect this drying. With this object in view the division wall 10 is made with a pair of internal flues 12 and 14 respectively communicating through flues 15 with the chambers high up on the division wall or slightly below the level of the flues 4. An underground flue 20 leads from beneath one end of the division wall and the flue 12 and flue 14 therein to the drying chamber indicated at 25, and these division wall flues communicate with the underground flue by flues 28 and 30 each controlled by a damper 31, the operating rod of which, 32, extends upwardly through the top of the wall.

The usual car tracks and cars, not shown, are provided for charging and discharging the kiln.

Each furnace is provided with a door 70 and dampers 75 by which the fire or burning action therein can be regulated to suit the requirements of the kiln; each chimney has a damper 80 by which the draft may also be regulated.

The superficial dimensions of the slabs of the grids are either equal to or a multiple of the, preferably, narrowest side of the brick to be burned in order that the bricks may be stacked thereon without obstructing the tortuous flues.

Operation: In charging my improved kiln the bricks from the drier are laid on cars and run into the kiln chambers where they are stacked in a way to permit an up-draft between them, the lower courses being stacked on the slabs of the grids only and not over the mouths of the tortuous flues. The preferred method of stacking my improved kiln and more particularly the two lowermost courses, to present draft inter-brick flues 100, is shown in Fig. 3. The bricks are built up to the top of the walls and consequently a short distance above the top of flues 4, the two top layers being set tight or platted. When the heating is started, either by building a fire on the grates or burning oil or gas in the furnace

chambers, the hot gas arises from the furnace chambers through the tortuous flue in the grids and upwardly through the interstices between the brick and are drawn toward the sides and ends of the kiln by the suction of the chimneys through the wall flues 4, the effect being that the heat is distributed throughout the entire chamber, and the burning and inflammable gases drawn by the independent flues 4 into the combustion chambers 3 are diffused therethrough and flow thence under the influence of the draft of the chimneys to the open air which they reach in a practically perfectly burned condition. Perfect control of the burning is obtained without disturbing the platting of the bricks within the chamber by the dampers in the furnace doors and chimneys; the comparatively large number of heat generators and chimneys permitting of such a distribution of heat throughout the kiln that the flow of burning gases is admitted throughout the entire area of the bottom of the burning chamber and the suction causes a constant flow upwardly between the bricks. If it is found that the burning operation is not being carried on uniformly and that too little or too great heat is occurring at any particular point, this particular point, wherever it may be in the kiln, can be readily reached and regulated by the heat generator and chimney controlling the zone in which it is located. When the burning operation in a kiln is finished and the dampers 31 and 80 controlling the communication with that kiln are opened, the other dampers being closed, the fire is drawn or the oil or gas shut off, the chimney dampers and furnace doors are kept open and a suction fan in the drying chamber is then started. The effect is that practically all the heat in the burning brick is drawn off and utilized in the drier.

The advantage of the kiln is that when in operation the heat is conserved to a maximum extent and the two or three top courses of bricks being set tight, what is known to the trade as platting, the chimneys and flues through the medium of the combustion chambers provide all the draft necessary to procure good and speedy burning with an open and up-draft kiln, and what could not be obtained heretofore without the enormously expensive down-draft type of closed kiln. And it is not necessary, as heretofore, with open top kilns, for the burner to repeatedly go on the top of the kiln to remove and replace bricks as required to control the draft and burning operations.

Considerable advantage is derived from the grids, in that the lower course of bricks are not subject to the initial heat of the burning gases which are deflected by the tortuous paths in the grids, thus breaking up the burning jets of gas and scattering

the heat in all directions from each of the upper slabs. This prevents fusing of the lower courses.

What I claim is as follows:

- 5 1. In a kiln for burning brick comprising side walls and end walls inclosing the kiln chamber with open top, a series of heat generators supplying gases at a high temperature to the bottom of the chamber, the combination with the chamber thus constructed, of means incorporated in the walls for causing an upward draft from the generators through the chamber to the top thereof for the purpose of permitting 10 stacked bricks within the chamber with their upper courses matted and approximately level with the top of the walls to be uniformly acted upon by the heat emanating from said hot gases.
- 15 2. In a kiln for burning brick comprising walls inclosing a kiln chamber with open top, a heat generator supplying gases at a high temperature to the bottom of the chamber, the combination with the chamber thus constructed of means incorporated in the said walls for causing an upward draft from the generators through the chamber to the top thereof for the purpose of permitting stacked bricks within the chamber with 20 their upper courses matted and approximately level with the top of the walls to be uniformly acted upon by the heat emanating from said hot gases.
- 25 3. An open-top up-draft kiln for burning brick consisting of a structure comprising side walls and end walls and a floor presenting a kiln chamber, said floor having heat generators set beneath the same and the portions of the floor above the generators having tortuous flues effecting communication between the generators and the kiln chamber, the side walls being provided with a plurality of chimneys forming perpendicular continuations thereof and horizontal flues 30 in the said side walls near their upper ends, the chimneys and flues being constructed and arranged to produce an outward draft from the kiln chamber to the chimneys.
- 35 4. An open-top up-draft kiln for burning brick consisting of a structure comprising side walls and end walls and a floor, presenting a kiln chamber, said floor having heat generators set beneath the same and the portions of the floor above the generators 40 consisting of a plurality of spaced layers of spaced slabs, the slabs of one series being arranged in staggered relation with the slabs of the other series and the slabs of the two series presenting in the spaces between the slabs and between the series tortuous flues effecting communication between the generators and the kiln chamber.
- 45 5. In an open-top kiln for burning brick, a heat generator; a flue beneath the floor 45 of the kiln and communicating with the heat generator; means forming a series of tortuous flues in the floor above the floor flues; a series of chimneys; a series of flues in the walls of the kiln near the top thereof and effecting communication between kiln 70 and chimneys, substantially as described and for the purpose of causing the uniform distribution of the heat through the kiln.
- 50 6. A kiln for burning brick having a chimney and a kiln-chamber, one of the 75 walls of which has a combustion chamber in direct communication at its top with the kiln-chamber and at its bottom with the chimney flue.
- 55 7. In a kiln for burning brick, consisting of a structure comprising side walls, end chambers; walls and floor presenting a kiln chamber, a chimney-flue, one of the side walls having a combustion chamber in direct communication at its top with the kiln 80 chamber and at its bottom with the chimney flue.
- 60 8. In a kiln for burning brick consisting of a structure comprising side walls and end walls presenting a kiln-chamber; the 85 side walls having intercommunicating combustion chambers and chimney-flues within the said side walls and the combustion chambers communicating with the kiln-chamber.
- 65 9. In a kiln for burning brick, consisting of a structure comprising side walls, end 90 walls and a floor presenting a kiln-chamber with open top, the side walls having combustion chambers and chimney-flues within the said side walls and the combustion chambers communicating with the kiln-chamber and chimney flues.
- 70 10. In a kiln for burning brick, consisting of a structure comprising side walls, end 100 walls and a floor presenting a kiln-chamber with open top, the side walls having combustion chambers and chimney-flues within the said side walls and the combustion chambers communicating with the kiln-chamber and chimney flues, and the said combustion chambers extending from end to end of the side walls.
- 75 11. In a kiln for burning brick, consisting of a structure comprising side walls, end 115 walls and a floor presenting a kiln-chamber with open top, the side walls having combustion chambers and chimney-flues within the said side walls and the combustion chambers communicating with the kiln-chamber and chimney flues and the said combustion chambers extending from end to end of the side walls and from within close proximity of the top of the walls to within a short distance of the base.
- 80 12. In a kiln for burning brick, consisting of a structure comprising side walls, end 120 walls and a floor presenting a kiln-chamber with open top, the side walls having combustion chambers and chimney flues within 125
- 85 13. In a kiln for burning brick, consisting of a structure comprising side walls, end 130 walls and a floor presenting a kiln-chamber with open top, the side walls having combustion chambers and chimney flues within

the said side walls and the combustion chambers communicating with the kiln-chamber, and the said combustion chambers extending from end to end of the side walls and 5 from within close proximity of the top of the walls to within a short distance of the base and the chimney-flues extending from the top of the walls to within a short distance of the base and the lower ends of the 10 chimney-flues communicating with the combustion chambers.

13. In a kiln for burning brick, consisting of a structure comprising side walls, end walls and floor presenting a kiln-chamber 15 with open top, each side wall having a combustion-chamber extending from within close proximity of the top to within a short distance of the base; a series of chimneys integrally with the top of the side walls and 20 flues extending from the chimneys downward within each side wall to the level of the bottom of the combustion chamber, and a series of flues in each side wall and effecting communication between the top of 25 the combustion chamber and the kiln-chamber.

14. In a kiln for burning brick consisting of a structure comprising side walls, end walls and floor presenting a chamber with 30 an open top, a plurality of parallel spaced heat generators located beneath the floor, a multiplicity of tortuous flues effecting communication between each of said generators and the chamber; a plurality of chimney 35 flues in each of said side walls and combustion chambers within the side walls and effecting communication between the chimney-flues and kiln-chamber.

15. In a kiln for burning brick, having a 40 kiln-chamber, a plurality of parallel spaced series of heat generators, a floor located above said heat generators and having an opening therein located directly over each of said generators, and means presenting a 45 multiplicity of tortuous flues effecting communication between said heat generators and said chamber consisting of a plurality of spaced layers of spaced slabs extending across each of said openings, the slabs of 50 one series being arranged in staggered relation with the slabs of the other series.

16. In a kiln for burning brick having a kiln-chamber, a plurality of parallel spaced 55 series of heat generators and having an opening therein located directly over each of said generators and means presenting a plurality of tortuous flues effecting communication between said heat generators and said chamber, said means consisting of a 60 plurality of layers or spaced slabs extending across each of said openings, the slabs of one layer being arranged in staggered relation with the slabs of the other layer and means formed integrally with the slabs 65 of one layer for spacing the layers.

17. A kiln consisting of a structure comprising side walls and end walls presenting an open-top kiln-chamber and a floor for said chamber having a plurality of openings therein with intervening dead floor sections; 70 means for heating said chamber, said means consisting of an excavation located directly beneath each of said openings and having a refractory lining, the inner end of said excavation being closed and the opposite end 75 opened, a furnace located at such opposite end and constituted by an excavation of greater depth than the first mentioned excavation and a grate located over such deeper excavation and in the horizontal plane of 80 the floor of the first mentioned excavation; and means presenting a multiplicity of tortuous flues effecting communication between the first mentioned excavation and said chamber, said means consisting of a layer 85 of spaced slabs extending across the top of said excavation with their ends resting upon the edges of the refractory lining; and a second layer of spaced slabs mounted upon the first mentioned layer in staggered relation thereto, the second layer having means formed integrally therewith for spacing the 90 same from the slabs beneath.

18. A kiln consisting of a structure comprising side walls and end walls presenting 95 an open-top kiln-chamber and a floor for said chamber having a plurality of groups of openings therein with floor members covering the same and presenting flues effecting communication between the openings 100 and kiln-chamber, means for heating said chamber, said means consisting of an excavation located directly beneath each of said groups of openings, the inner end of said excavation being closed and the opposite end 105 open and a furnace located at such opposite end.

19. In an open top kiln, an intermediate transverse wall dividing the same into a pair of kiln-chambers; flues in said division 110 wall and communicating with the respective kiln-chambers near the top thereof and a flue communicating with both of the said wall flues for effecting communication therebetween and a drier; and dampers controlling the communication between the last mentioned flue and the said pair of wall flues, for the purpose of transmitting to the drier the waste heat from said kiln chamber or kiln chambers. 115

20. In a kiln, an intermediate wall dividing the chamber into a pair of kiln chambers and having a pair of flues therein, a flue effecting communication between each kiln chamber and one of said first mentioned 125 pair of flues, an underground flue communicating with said pair of flues for transmitting to a drier the waste heat from the kiln-chamber or kiln-chambers, and means for controlling the communication between the 130

underground flue and each of said first mentioned flues, said means consisting of a pair of dampers and operating rods connected to the dampers and extending through the top of the division wall for the purpose set forth.

In testimony whereof I have signed my

name to this specification in the presence of two witnesses.

LACHLAN W. McARTHUR.
